CLAIM

The ornamental design for a charging station, as shown and described.

DESCRIPTION

FIG. 1 is a front perspective view of the charging station showing our new design;

FIG. 2 is a rear perspective view thereof;

FIG. 3 is a front elevational view thereof;

FIG. 4 is a rear elevational view thereof;

FIG. 5 is a left-side elevational view thereof;

FIG. 6 is a right side elevational view thereof;

FIG. 7 is a top plan view thereof; and,

FIG. 8 is a bottom plan view thereof.

The broken lines immediately adjacent to the shaded areas represent the bounds of the claimed design, while all other

(Continued)

broken lines depict portions of the charging station that form no part of the claimed design; the broken lines form no part of the claimed design.
